UNITED STATES PATENT OFFICE.

VICTOR L. BENTSON, OF SAN FRANCISCO, CALIFORNIA, ASSIGNOR TO NATIONAL PROGRESS CLUB, OF SAN FRANCISCO, CALIFORNIA, A CORPORATION OF CALIFORNIA.

DESIGN FOR AN EMBLEM, BUTTON, BROOCH, FOB, OR SIMILAR ARTICLE.

Application filed August 19, 1922. Serial No. 3,468. Term of patent 14 years.

To all whom it may concern:

Be it known that I, VICTOR L. BENTSON, a citizen of the United States, whose post-office address is 1201 Nevada Bank Building, San Francisco, California, have invented a new, original, and ornamental Design for an Emblem, Button, Brooch, Fob, or Similar Article, of which the following is a specification, reference being had to the accompanying drawing, forming part hereof.

The figure is a plan view of an emblem, button, brooch, fob or similar article, showing my new design.

I claim:

The ornamental design for an emblem, button, brooch, fob, or similar article as shown.

VICTOR L. BENTSON.
